CHARLES W. HURL, OF NANTYGLO, PENNSYLVANIA, ASSIGNOR TO J. W. KEPHART
AND J. W. LEECH, BOTH OF EBENSBURG BOROUGH, PENNSYLVANIA.

AUTOMATIC RELEASE VALVE FOR AIR-BRAKE SYSTEMS.

1,406,020.

Specification of Letters Patent.

Patented Feb. 7, 1922.

Application filed August 11, 1921. Serial No. 491,441.

To all whom it may concern:

Be it known that I, CHARLES W. HURL, a citizen of the United States, residing at Nantyglo, in the county of Cambria and State of Pennsylvania, have invented certain new and useful Improvements in Automatic Release Valves for Air-Brake Systems, of which the following is a specification.

10 This invention relates to the air brake systems of railway trains, and has for its principal object to provide a simply constructed attachment whereby the engineer will be able to hold the brakes of the forward cars applied while the brakes of the rear cars are being released.

Another object of the invention is to provide a device of this character which may be coupled into the ordinary train pipe of 20 the air brake system without structural change in the system and without interfering with the ordinary operations of the same.

With these and other objects in view, the 25 invention consists in certain novel features of construction as hereinafter shown and described and then specifically pointed out in the claims, and in the drawings illustrative of the preferred embodiment of the invention:

Figure 1 is a side elevation of a portion of a conventional air brake system with the improved attachment applied.

Figure 2 is an enlarged sectional elevation 35 of the improved attachment.

Figure 3 is a transverse section on the line 3—3 of Fig. 2.

Figure 4 is a detached bottom plan view of the piston head.

40 The improved device comprises a tubular body 10 having transverse diaphragms or partitions 11 and 12 intermediate the ends and in spaced relation and a closure cap 13 in advance of the diaphragm 11. The portion of the body between the diaphragm 12 and its lower end is bored to receive a piston head 14 air tight, the latter having a stem or rod 15 extending through an opening in the diaphragm 12, and terminating in a 45 needle valve 16 adapted to engage a seat 16 in the diaphragm 11 when the rod 15 is elevated.

The rod 15 is threaded where it passes

through the piston 14 to receive an adjusting nut 18, to enable the piston to be adjusted on the rod. 55

The rod 15 is likewise threaded intermediate the ends as at 19 to receive adjusting nuts 20 to enable the position of the rod to be adjusted relative to the diaphragm 12 to 60 control the action of the valve 16.

A spring 21 is disposed between the piston 14 and the diaphragm 12, and operates to hold the piston yieldably in its downward position and the valve 16 normally open. 65

An exhaust pipe 22 is coupled into the body 10 between the diaphragms 11 and 12 and a relatively large opening 23 is also formed in the body 10 between the diaphragms 11 and 12, to provide access to the 70 interior of the body to enable the nuts 20 to be adjusted. The opening 23 is provided with a detachable closure 24 bolted or otherwise secured to the body and suitably packed to hold the pressure. 75

The body 10 is designed to be coupled to the train pipe of the air brake system a portion of which is represented at 25, at any convenient point, preferably near the triple valve, represented conventionally at 80 26. The attachment may be connected in any suitable manner, for instance by a conventional coupling 27, and will preferably be off-set from the train pipe.

A relatively small pipe 28 is connected to 85 the exhaust 29 of the triple valve 26 and is turned over as shown at 30 and connected through the cap 13 as shown in Fig. 2.

A portion of the brake cylinder is represented at 31, the auxiliary reservoir at 32 90 and the connection between the train pipe 25 and triple valve at 33, these parts being of the usual construction.

One set of the parts 31, 32 and 33 is attached to each car of the train in the usual 95 manner, and one of the improved attachments associated with each of the triple valves.

When the engineer operates the valve in the locomotive cab to reduce the pressure in 100 the train line in the ordinary manner, to apply the brakes, the pressure to the brake cylinder of the forward car or the one nearest the engine, is reduced first, consequently the brakes on the first car are applied first. 105

In the improved device the springs 21 are set to resist the normal pressure in the train pipe, usually about 70 pounds to the square inch for freight trains to which 5 the improved device is more particularly applicable.

With the improved device applied to the triple valve exhaust of each car, the engineer, when the brakes are to be released, 10 moves the controlling lever in his cab to full release position which action opens the way between the main supply reservoir on the locomotive and the train line, the pressure in which has been reduced about 10 pounds 15 more or less, in applying the brakes. The pressure in the train line is thus raised at the part nearest the locomotive to nearly or quite equal to the pressure in the supply tank, or about 100 pounds and is gradually 20 lessened toward the rear of the train to about 65 pounds.

The high pressure from the storage tank thus flows to the train line and increases the train line pressure at the front thereby 25 causing the valves 16 in this part of the train to be closed and shutting off the exhaust from the triple valves by holding the valves 16 closed as far back in the train as the excess pressure exceeds the normal pressure of 70 pounds, but with the valves 16 30 toward the rear, or those subject to a pressure of 70 or less, open, and with the exhaust from the triple valves at the rear also open.

By this means the brakes at the front 35 are retained in applied position so long as the pressure in the train pipe is above the normal, or 70 pounds, leaving the brake at the rear free to be released first, as the valves 16 at the rear remain open owing 40 to the relatively low pressure, as before stated.

By this simple arrangement the engineer can easily control the action, and cause the brakes to be released from the rear toward 45 the front of the train and effectually prevent the "piling up" of the cars, or the pulling of draw heads, so liable to occur with the ordinary arrangement when the engineer is careless or inexperienced.

50 With the improved device applied, the rear brakes will be automatically released

first, regardless of any false movements which the engineer can make.

The preferred embodiment of the invention is disclosed in the drawings and set 55 forth in the specification, but it will be understood that any modifications within the scope of the claimed invention may be made in the construction without departing from the principle of the invention or sacrificing any of its advantages. 60

Having thus described the invention, what is claimed is:—

1. An automatic release valve for air brake systems comprising a casing closed at one 65 end and open at the other end and adapted to be coupled at its open end to the train pipe of the system, said casing having transverse diaphragms in spaced relation intermediate the ends with a valve seat in one of 70 the diaphragms, a piston operating in the casing at its open end, a stem extending from the piston and through the other diaphragm and terminating in a valve adapted to engage the seat, a spring operating to maintain said piston at one end of its stroke and the valve open, and a conductor element connecting with said casing and adapted to be coupled to the triple valve of the system. 75

2. An automatic release valve for air brake 80 systems comprising a casing adapted to be coupled between the train pipe and the exhaust of the triple valve, said casing having an intermediate valve seat, a piston operating in the casing, a stem extending from 85 the piston and terminating in a valve adapted to engage the seat, and a spring operating to maintain said piston in position to hold the valve open.

3. An automatic release valve for air brake 90 systems comprising a casing adapted to be coupled between the train pipe and the exhaust of the triple valve, said casing having a valve seat, piston operating in the casing, a stem extending from the piston and terminating in a valve adapted to engage the seat, and a spring operating to maintain said 95 piston in position to hold the valve open.

In testimony whereof, I affix my signature hereto.

CHARLES W. HURL.
